Primary Examiner — Karen S Acker(74) *Attorney, Agent, or Firm* — Dorsey & Whitney LLP(57) **CLAIM**

We claim the ornamental design for a rail for a covering for an architectural opening, as shown and described.

DESCRIPTION

FIG. 1 is a top-left isometric view of a rail for a covering for an architectural opening.

FIG. 2 is a detail, top-left isometric view of the rail of FIG. 1 bounded by the detail line 2-2 as shown in FIG. 1.

FIG. 3 is a front elevation view of the rail of FIG. 1 as shown in FIG. 2.

FIG. 4 is a bottom plan view of the rail of FIG. 1 as shown in FIG. 2; and,

FIG. 5 is a left side elevation view of the rail of FIG. 1. The broken lines, which define the bounds of the claimed design, form no part of the claimed design.
